TOY

Harry J. Criner, Davenport, Iowa, assignor of
one-half to A. G. Bush, Davenport, Iowa

Application July 28, 1945, Serial No. 607,594

14 Claims. (Cl. 46—114)

1

My invention relates to a new and useful toy.

The objects of my invention are to provide a toy which will simulate a gun or cannon and which may be actuated either manually or by wheels arranged to travel over a floor or walk; also to provide a mechanical movement applicable to a variety of uses.

I accomplish these objects by the means shown in the accompanying drawings, in which—

Figure 1 is a top or plan view of one form of my apparatus, with a portion of the frame and handle in section on the line 1—1 of Figure 2;

Figure 2 is a vertical section on the line 2—2 of Figure 1;

Figure 3 is a top view of another form of my apparatus in which the handle is applied separately from the actuating mechanism;

Figure 4 is a side elevation of Figure 3 but with the near side wheel omitted; and

Figure 5 is a sectional elevation of a modified form of my apparatus in which projectiles may be utilized and fired from the gun barrel.

In the simplest form my apparatus comprises a frame 1 which may be of wood, metal or other suitable material in the form of a yoke with hubs 2—2 formed integral therein in which an axle shaft 6 is mounted. The axle shaft is revolvable in the hubs 2 and may have rigidly secured to the outer ends thereof supporting wheels 4 and 5, each hub 2 being formed with a bore 3 in which the axle shaft 6 may be rotatably secured.

Midway of the shaft 6 a retractor 15 is secured which may be formed as a rectangular plate or as a single or double yoke of metal rod and secured in the axle shaft by a pressfit or by set screws 6.1 or other suitable means.

To the frame 1 a handle 7 is secured by pressfit or other suitable means. The handle 7 may be a hollow metal tube or barrel or may be a wooden bar with a bore 7.1 formed therein extending from the lower end of the handle for any desired distance. In the bore of the barrel a rod or plunger 10 is slidably mounted and the lower end of the plunger 10 is slotted to receive the outer end end of a bar 12 which is secured to the lower end of the plunger by a pivot pin 11, or other suitable means.

The lower end of the bar 12 has points 13—13 extending upwardly and downwardly therefrom, with the intermediate portion of the bar forming a head spaced a short distance from the periphery of the shaft 6, the points 13 being arranged in a position to be contacted by the retractor 15 as it revolves and carried therewith as it revolves until the bar 12 reaches its rearmost point of travel and comes in contact with the

2

shaft 6, at which time the retractor will leave contact with the point 13 releasing the bar and permitting the plunger 10 to return to its normal position. The points 13 may extend both upwardly and downwardly from the bar 12 to be caught by the yoke 15 when revolving in either direction and the bar retracted as described.

In order to hold the axis of the bar 12 in line with the center of the shaft 6, I form the front end of the bar 12 with a flat face and provide a flat-faced plug 16 to bear against it. The plug 16 is slidably mounted in a bore 16.1 and a compression spring 17 is mounted in the bore 16.1 to bear lightly against the forward end of the plug 16.

The plunger 10 is provided with a pin 22 which is slidably mounted in a slot 7.2 formed in the handle 7 and acts to limit the longitudinal travel of the plunger 10.

20 The outer ends of the pin 22 engage a ring 23 slidably mounted upon the outside of the handle 7. Additional rings 23.1 and 23.2 extend around the handle and are freely slideable longitudinally thereon.

25 A tension spring 19 is fitted in the bore 7.1 and its rear end is pivotally united to the plunger 10 and its front end pivotally united to the handle 7 by a pin 20 or other suitable means.

In the operation of my device, as the wheels 4 and 5 are rolled along the floor, they rotate the shaft 6 which carries with it the retractor 15 and as it revolves, its ends successively contact the points or extensions 13 and retract the bar 12, thus exerting tension on the spring 19 to draw it to its designed limit of extension, at which

30 point the yoke of the retractor 15 by its further revolution releases the contacted point 13 and permits the spring 19 to forcibly and quickly return the plunger 10 to its normal position, carrying with it the pin 22 which carries the ring 23.

35 The ring 23 then forcibly strikes the ring 23.1 and impels the rings 23.1 and 23.2 outwardly upon the handle to a distance commensurate with the force applied by the spring 19. If the handle 7 is held in an inclined or vertical position, the rings will then descend to their at-rest position ready to be actuated again by the next half revolution of the retractor 15 and this operation will be repeated at rates depending upon the speed with which the wheels 4 and 5 are drawn along the floor or walk.

The frame 1, shaft 6, and wheels 4 and 5, are made of sufficient weight and the wheels are given a peripheral surface such as rubber or other frictional material which will cause them to contact the floor, carpet or walk, with sufficient pres-

sure and friction to cause the wheels to revolve and carry the shaft 6 against the force of the spring 19.

In Figures 3 and 4 alternative forms of this device are shown in which the mechanism above described is arranged in connection with a gun barrel 28 having a bead or stop ring 27 formed at its front end which will stop the rings 23.1 and 23.2 at a given point of its travel.

In Figures 3 and 4 the handle 7 is shown attached to the frame 1 by a sleeve 25 united to a plate 24 and secured to the frame by screws or bolts 26. The outer end of the handle in this case may be provided with a crossbar 25 for convenience in handling.

The noise produced by the plunger when returning to its position and by contact of the ring 23 with the ring 23.1, will make a sound resembling to some extent the firing of a gun and the forward movement of the rings 23.1 and 23.2 along the barrel will imitate to some extent the forward movement of a projectile and if painted red or orange color, they will imitate to some extent the burst of flame accompanying the discharge of a gun.

When desired to simulate the action of a gun more closely, the bore 7.1 may extend through the entire length of the barrel 28. The plunger 10 may be formed with a rod 10.1 extending forwardly therefrom entirely through the length of the spring 19 and arranged to strike a small ball or marble 33 as shown in Figure 7.

In the wheeled form, with separate handle and gun barrel, the toy may be used as an imitation of mobile artillery.

Various modifications may be made in the form and arrangement of the parts of my apparatus without departing from the spirit of my invention and the actuating mechanism may be applied to various other uses, and I do not limit my claims to the precise forms nor to the particular uses specified.

I claim:

1. A toy comprising a frame, a shaft revolvably mounted on the frame, a pair of spaced supporting wheels united to the shaft, a retractor united to and rotating with the shaft and having an arm projecting radially therefrom, a hollow arm or barrel having one end secured to the frame and the other end extending outwardly therefrom, a plunger slidably mounted in the arm or barrel, a bar having one end pivoted to one end of the plunger and its opposite end provided with a projection or catch arranged to be engaged and drawn backward by the rotating retractor to a predetermined point and then automatically released from the retractor, a spring mounted in the hollow arm or barrel arranged to exert tension forwardly upon the plunger and to drive it forwardly when the bar is released from the retractor, and means to rotate the shaft.

2. A mechanism comprising supporting wheels, a shaft united to the wheels and revolvable therewith, a retractor united to the shaft and having arms projecting radially therefrom in opposite directions, a frame carried by the shaft, a hollow arm or tube having one end secured to the frame and the other end extending outwardly therefrom, a rod slidably mounted for reciprocation in the tube, a bar having one end pivotally united to the rod and its opposite end provided with a projection or catch arranged to be engaged and drawn rearwardly by the retractor as it rotates with the shaft to a predetermined point and then automatically released from the retractor, a

spring mounted in the tube arranged to drive the rod forwardly when it is released from the retractor, and means to rotate the shaft.

3. A mechanism comprising a pair of supporting wheels, a shaft rigidly united to the supporting wheels and carrying a frame in which the shaft is revolvable, a retractor united to the shaft and projecting laterally therefrom, a hollow arm or tube having one end secured to the frame and the other end extending outwardly therefrom, a rod slidably mounted for reciprocation in the tube, a bar having one end pivotally united to the rod and its opposite end provided with a projection or catch arranged to be engaged and drawn toward the shaft by the retractor as it rotates with the shaft to a predetermined point and then automatically released from the retractor, a spring mounted in the tube and connected to the tube and the rod to propel the rod outwardly when released from the retractor.

4. A mechanism as described in claim 2, a longitudinal slot formed in the tube, and a pin mounted in the plunger extending outwardly through the slot and into an external ring slidably mounted upon the tube.

5. A mechanism as described in claim 2, a longitudinal slot formed in the tube, a pin mounted in the plunger extending outwardly through the slot and into an external ring slidably mounted upon the tube, and an additional ring freely slideable upon the barrel in position to contact and be actuated by the pinned ring.

6. A mechanism as described in claim 2 an external ring slidably mounted upon the tube, and means united to the plunger and said external ring to hold them in fixed relative position to each other.

7. A toy as described in claim 1, the barrel being extended to form a handle.

8. A toy as described in claim 1, and a handle united to the frame opposite the barrel.

9. In a toy, the combination with a frame, of a shaft rotatably mounted therein, supporting wheels secured upon the shaft, a tubular handle having one end united to the frame, a ring slidably mounted upon the handle near the frame, and coacting means carried by the handle and the shaft arranged to intermittently impel the rings outwardly along the handle.

10. A toy mobile artillery unit comprising a pair of supporting wheels united by a shaft fixed thereto and rotatable with the wheels, a frame mounted upon the shaft, a barrel having one end secured by the frame and extending outwardly at a right angle to the shaft, a plunger slidably mounted in the barrel and spring-held in normal forward position, coacting means mounted upon the shaft and the plunger arranged to intermittently retract the plunger from its normal position and to release it at a given point.

11. A toy unit as described in claim 10, and rings slidably mounted upon the barrel, contacting means united to the plunger arranged to drive the rings outwardly along the barrel when the plunger returns to normal position after each release.

12. A toy comprising a frame, a shaft revolvably mounted on the frame, a pair of spaced supporting wheels united to the shaft, a retractor united to and rotating with the shaft and having an arm projecting radially therefrom, a hollow arm or barrel having one end secured to the frame and the other end extending outwardly therefrom, a plunger slidably mounted in the arm or barrel, a bar having one end pivoted to

5

one end of the plunger and its opposite end provided with opposed projections arranged to be engaged and drawn backward by the rotating retractor to a predetermined point and then automatically released from the retractor, a spring mounted in the hollow arm or barrel arranged to exert tension forwardly upon the plunger and to drive it forwardly when the bar is released from the retractor, and means to rotate the shaft.

13. A mechanism comprising supporting wheels, a shaft united to the wheels and revolv-
able therewith, a retractor united to the shaft and having arms projecting radially therefrom in
opposite directions, a frame carried by the shaft, a hollow arm or tube having one end secured to
the frame and the other end extending outwardly therefrom, a rod slidingly mounted for recipro-
cation in the tube, a bar having one end pivotally united to the rod and its opposite end provided
with opposed projections arranged to be engaged and drawn rearwardly by the retractor as it ro-

5

tates with the shaft to a predetermined point and then automatically released from the retractor, a spring mounted in the tube arranged to drive the rod forwardly when it is released from the retractor, and means to rotate the shaft.

10

14. In a toy, the combination with a hollow bar, of a plunger slidingly mounted within the hollow bar, a rod united to the plunger and extending rearwardly therefrom, a retractor revolvably mounted at a given space from the rear end of the bar, means to support the bar and the retractor in fixed relative position, means united to the rear end of the rod arranged to be engaged by the retractor as it is revolved to draw the rod and plunger rearwardly for a predetermined distance and then to release the rod, resilient means united to the plunger and the bar to drive the plunger forward when the rod is released from the retractor and means to revolve the retractor.
